Primary Examiner — Susan Moon Lee(74) *Attorney, Agent, or Firm* — John D. Gugliotta**CLAIM**

The ornamental design for an angled pet feeder, as shown and described.

DESCRIPTION

FIG. 1 is a top front perspective view of an angled pet feeder showing my new design in use;

FIG. 2 is a bottom front perspective view thereof;

FIG. 3 is a bottom plan view thereof;

FIG. 4 is a top plan view thereof; and,

FIG. 5 is a right side elevational view, the left side being a mirror image thereof.
